UNITED STATES PATENT OFFICE

95,564

DESIGN FOR A DRESS

Samuel Zahn, New York, N. Y.

Application April 1, 1935, Serial No. 56,172

Term of patent 3½ years

To all whom it may concern:

Be it known that I, Samuel Zahn, a citizen of the United States of America, residing in Manhattan, county of New York, and State of New York, have invented a new, original, and ornamental Design for a Dress, of which the following is a specification, reference being had to the accompanying drawing, forming part thereof, wherein,

The lines across the front and back of shoulders represent shirring. The vertical lines on the front portion of the skirt represents stitched pleats.

I claim:

The ornamental design for a dress, substantially as shown and described.

SAMUEL ZAHN.
